UNITED STATES PATENT OFFICE.

THOMAS H. SEELY, OF MALDEN, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed July 22, 1920. Serial No. 393,056.

The present invention is herein shown and described with particular reference to its application to machines for inserting fastenings in lasting boots and shoes, although in 5 various of its aspects it is not restricted to such use. In the drawings the invention is illustrated as embodied in a lasting machine which works on different portions of the upper materials successively, the machine 10 being of the type known as the hand method machine. A machine of this type is disclosed in Letters Patent of the United States No. 584,744, granted June 15, 1897, upon application of Ladd & McFeely.

15 In the use of machines of this general type, particularly such machines as embody the invention of Letters Patent of the United States No. 1,477,011, granted December 11, 1923, on my application for side lasting shoes, particularly welt shoes, it is required to drive two widely different kinds of fastenings, for example a three and one-half or four ounce tack for lasting the sides, which is a longer tack than the machine as 20 previously built is designed to handle, and a small tack, for example a one and one-half ounce tack, for the heel seat. A single separator operates to separate a tack of either kind, the raceway being moved to 25 present in operative relation to the separator either the tack channel containing the long tacks or the tack channel containing the short tacks. An object of the present invention is to provide a machine in the use of 30 which the separation of a tack in each cycle of the machine will be assured whether the mechanism is set to deliver a short tack or a long tack and notwithstanding wide divergence in the length of the tacks, failure of 35 the separator to separate a tack at each operation, unless a malformed tack is presented to the separator or some other accident occurs, being eliminated.

40 The raceways of the machine are usually arranged at an angle of thirty degrees to the horizontal, this having been found ample to insure that the tacks will move by gravity down the raceway channels with the tack heads in "shingled" relation, that is, with the 45 head of a lower tack under the head of the next higher tack. The stems of the tacks in the raceway channels do not hang exactly

vertical but incline approximately ten or twelve degrees toward the tack pot at an angle to the vertical which may be called the 55 natural hanging angle of the tack. The tack gate, which closes the end of the raceway after a tack has been separated by the separator blade, is in a vertical plane as is also the tack passage into which the tack 60 is drawn by the blade and released and through which the tack falls after its separation into the tack pocket in the wiper then located beneath it. After much experimentation it was discovered that tack separation 65 would be facilitated and insurance could be provided against clogging of tacks, if the direction of the tack separator passage and the plane of reciprocation of the tack gate were arranged out of the vertical and more 70 nearly at the natural hanging angle of the tack stems in the raceway. Accordingly a feature of the present invention consists in an organization including an inclined raceway having a plurality of channels in which 75 the tack stems hang at an angle to the vertical, and a separator for separating tacks from either channel in the raceway and releasing them in a tack passage through 80 which each tack falls after separation, said 85 passage being inclined at an angle to the vertical approximating the natural hanging angle of the tack stems in the raceway. Preferably the tack gate is arranged to reciprocate in a plane parallel to the direction 90 of the tack passage and hence at a similar angle to the vertical. It has been found that the angle of the passage and gate need not equal the inclination of the tacks, although under some conditions such a construction 95 may be desirable, for if the inclination of the passage and gate is substantial, say six degrees to the vertical, tack separation is effected perfectly and failure of separation does not occur.

100 In machines of this type as previously constructed the raceway has been made in two parts jointed together near the tack pot to permit a swinging movement of the lower portion of the raceway so that either tack channel could be positioned in operative relation to the separator. It is desirable, in order to insure free passage of the tacks along the tack channels, that the channels be

continuous from end to end. Accordingly a feature of the invention consists in a raceway provided with tack channels which extend from the interior of the tack pot to the separator without movable joint, the raceway being arranged for movement about a virtual pivot at its point of passage through the wall of the tack pot.

It is desirable that the lower end of the raceway be carefully adjusted with relation to the tack separator to insure free movement of the separator, to enable slight inaccuracies in machining of the parts to be taken care of without laborious fitting, and to compensate for maladjustment resulting from wear or other causes. A feature of the invention consists, therefore, in a raceway arranged for movement longitudinally and means for effecting a fine adjustment of the raceway longitudinally toward and from the separator.

Another feature of the invention consists in an improved organization including the novel construction and arrangement of tack pot, raceways and separator as above described, with an edge gage movable into and out of operative position, and power means under control of the operator for moving the gage into and out of operative position and for shifting the raceways to control the size of the tack.

These and other features of the invention will appear more fully from the following description when read in connection with the accompanying drawings and will be pointed out in the appended claims.

In the drawings,

Fig. 1 is a side elevation of a machine embodying the present invention, the base of the machine being omitted and the column partly broken away;

Fig. 2 is a detail in side elevation, partly in section, of parts shown in Fig. 1;

Fig. 3 is a plan view of the edge gage shifting mechanism;

Fig. 4 is a detail in elevation of parts shown in Fig. 3;

Fig. 5 is a sectional detail of parts shown in Fig. 4;

Fig. 6 is a plan view of the knee lever and connected mechanism;

Fig. 7 is a detail of the roll carrying arm of the gripper closing rockshaft;

Fig. 8 is a detail, partly in section, of the updraw lever fulcrum pin and parts shown in Fig. 7;

Fig. 9 is a side elevation of the tack pot and raceway;

Fig. 10 is a sectional detail of the tack separator and the lower end of the raceway;

Fig. 11 is a detail in perspective of parts shown in Fig. 9;

Fig. 12 is a plan view of the tack pot and raceway; and

Fig. 13 is a sectional view of the tack pot.

Referring to Fig. 1 of the drawings, which shows in side view the machine head and a column 2, partly broken away, upon which the head is mounted, the numeral 4 indicates a driving pulley and 6 a shaft which carries the cams from which the operative movements of the machine are derived. A gripper 10 is given the usual closing, up-draw and overdraw movements by mechanism similar in function to that shown in the patent to Ladd & McFeely above referred to except in respects hereinafter noted. The shoe bottom is held against a rest 12 with its side positioned against one or the other of two edge gages 13, 14. A reciprocating wiper 15 is provided to wipe the tensioned upper into lasted position upon the shoe bottom and a tack is fed in each cycle of the machine from one or the other of two raceway channels 16, 17 to a pocket in the wiper by which it is carried in position to be driven by a driver 18. The wiper is carried by a horizontally reciprocating slide 19 which is actuated by a lever 20 operated by a cam 21 on the shaft 6. Tacks are partially driven when driver stops 22 are positioned beneath a collar 23 upon the driver bar and are completely driven when the stops 22 are removed from beneath the collar 23, the stops being operated by rocking movement of a vertical shaft 24.

Mechanism is also provided as in prior machines of this type for giving the gripper its lateral and turning movements, these movements being initiated and controlled in extent by movement of a yoke 25 having rolls which engage a groove in a collar 26. Movement of the yoke 25 is effected by rocking movement of a vertical shaft 27 through connections to a pleater lever 28 pivoted at 29, lateral movements of which are utilized to rock the shaft 27 by means of the mechanism shown in Figs. 1 and 6. The pivot 29 of the pleater lever 28 is a stud fixed by a set screw 30 in a bracket 32 fixed to lugs 33 on the column by bolts 34. The pleater lever 28 has on its rear end segment teeth which engage corresponding teeth in a segment piece 36 clamped by screws 37 to the vertical shaft 27. Lateral movement of the lever 28 will, by the mechanism described, cause rocking movement of the shaft 27 and hence of the yoke 25 to control the pleating movements of the gripper 10. To yieldingly maintain the pleater lever in various position of adjustment and to enable the operator, by the feel, to tell when the pleating mechanism is properly set, an arm 38 is clamped by screws 39 to the rockshaft 27 and extends to a position over the stud 29 on which the pleater lever 28 is pivoted. In the stud 29 is an upwardly spring-pressed plunger 40 arranged to engage one of a number of recesses in the lower face of the arm 38. The pleater lever 28 is operated by a

knee fork 42 adjustably secured to a bar 44 which is pivoted at its rear end on a rod 46 and has a slot 48 engaged by a roll stud 50 on the pleater lever 28. Lateral movement 5 of the knee fork 42 and bar 44 will, therefore, cause movement of the pleater lever 28 as and for the purpose described. Movement of the pleater lever 28 is adjustably limited, in one direction, by a screw 52 10 threaded into it and arranged to engage the column 2, and, in the other direction, by a screw 54 threaded through a lug on the bracket 32 and arranged to be engaged by a projection 56 of the lever 28.

15 The position of the edge gages 13, 14 and the operation of other mechanism to be described is controlled by longitudinal movement of the bar 44, effected through mechanism now to be described, by inward pressure of the operator's leg on the knee fork 42, such movement being permitted by the slot 48. The rod 46 which forms the pivot of the bar 44 carries a collar 57 fixed thereto by a set screw 58 to support the bar 44 and 20 extends upward through two bearings 59, 60 in a member 62 which is loosely mounted on the rockshaft 27 by two bearings 64, 66. The member 62 has a rearward extension 68 having therein a spring plunger 70 which bears 25 against the column 2 and acts through the member 62 to hold the bar 44 normally in an outward position. Movement of the member 62 is limited by stop screws 63, 65 threaded through the member 62 and arranged alternately to engage the column 2 in the respective limited positions of the movement 30 of the member. The rod 46 is clamped near its upper end in the bearing 60 by a screw 61 and at its upper end has an angularly 35 disposed portion formed as a dog 72 to engage a notch in a sleeve or tube 74 surrounding the rockshaft 27. The dog 72 forms an operative connection between the sleeve 74 and the push bar 44 so that when the bar is 40 pushed inwardly or rearwardly of the machine the member 62 will be rocked about the shaft 27 as an axis against the spring plunger 70 and the dog 72 will cause a slight 45 rotation of the sleeve 74 about the shaft 27.

50 This slight rotation is effective, by mechanism now to be described, to cause power shifting of the edge gages 13, 14, movement of the driver stops 22 to change the stroke of the driver, and movement of the raceway 55 to bring one or the other of the tack channels 16, 17 into operative relation to the separator and thereby change the kind of tacks supplied to the wiper 15. The upper end of the sleeve 74 is reduced and one branch 79 of a 60 Y-shaped member is clamped to the reduced portion of the sleeve by a screw 81. The other branch 82 of the Y-member is mounted loosely on the rockshaft 27. The stem of the Y-member is formed as a handle 83 by 65 which the sleeve 74 may be rocked by hand

if desired. Mounted on a pin 84 in the upper face of the portion 81 of the Y-member is a pawl 86 (Fig. 3) which is held by a spring 87 in engagement with a ratchet 88 shown as having six teeth. The ratchet is 70 loose on the shaft 27 and has fixed to its upper face a cam 90 having three projections and between the projections three depressions. The cam 90 acts on two rolls 92, 94 mounted on the lower face of a sliding 75 member 96 which is provided with a slot 98 embracing a block 100 loosely mounted on the shaft 27. When the cam is rotated one-sixth of a revolution one projection of the cam 90 will leave one of the rolls 92, 94, for instance 80 the roll 92, while another projection will engage the other roll, for instance the roll 94, causing the sliding member 96 to be moved, the movement, in the instance cited, being an outward movement. Upon further 85 movement of the cam in the same direction one-sixth of a revolution the sliding member 96 will be returned to the position shown.

To effect rotation of the ratchet 88 and the cam 90 by power a bracket 102 is secured 90 to the wiper slide 19 by a cap screw 104, the bracket being slotted to permit forward and rearward adjustment of the bracket when the screw is loosened. A fine adjustment for the bracket is provided by a screw 106 threaded 95 into the bracket 102 and having a capstan head which abuts against a boss 105 on the slide 19. A set screw 108 is provided to hold the screw 106 in adjusted position. A pawl 110 is pivoted by a pin 112 to the bracket 102 100 and has a tail 114 which determines the normal position of the pawl 110 by engagement with a flat face formed on the bracket 102, in which position the pawl is held by a spring plunger 116 mounted in the bracket 102 105 and engaging the forward portion of the pawl. As the slide 19 is reciprocated the outer flat face of the pawl 110 moves back and forth parallel with one of the flat faces 118 formed between the teeth of the ratchet. 110 When, however, it is desired to cause shifting of the edge gages and other mechanism, the ratchet is given enough movement either by the knee fork 42 or by the hand lever 83 to cause a tooth of the ratchet 88 to pass the 115 pawl 110, whereupon the slide 19, in its next forward reciprocation, will rotate the ratchet 88 and cause the sliding member 96 to be moved forward if in its rearward position or rearward if in its forward position. To prevent accidental backward movement of the ratchet 88 in either position of the sliding member 96 a pawl 91 is provided on the stud 120 which holds the roll 94 and has two teeth 93, 95, the tooth 93 being in position to engage a tooth of the ratchet when the sliding member is in the position shown in Fig. 3 and the tooth 95 being arranged to engage a tooth of the ratchet when the member 96 is moved 125 to its forward position. The pawl 91 is held 130

against the ratchet by a spring 97 and its toothed portion lies over the pivot pin 84 of the pawl 86 to prevent upward movement of the pin. The toothed portion of the pawl 91 is extended at 99 so that it overlies the pin in all positions of the sliding member 96. The sliding member 96 is pivoted by a pin 120 to an irregularly shaped lever 122 best shown in Fig. 4. The lever 122 is fulcrumed on the driver stop shifting shaft 24 which has two bearings 124, 125. The lever 122 is formed to embrace the bearing 125 and to have a bearing 126 on the shaft 24 above the bearing 125 and another bearing 128 below the bearing 125 where it is secured to the shaft by a set screw 130. Movement of the lever 122 is thus operative to rock the shaft 24 and shift the driver stops 22 into and out of position under the collar 23. A block 132 (Figs. 4 and 5) is adjustably secured in a recess in the lever 122 by a cap screw 134. The lower portion of the block 132 has a recess open at its side to receive the end of a link 135 which is connected at its other end 25 to the raceway 136 by a ball and socket joint 137. Preferably the link 135 is made adjustable for length by being made in two parts threaded together and provided with a set nut 138 to maintain the adjustment. In the block 132 is mounted a spring plunger 139 (Fig. 5) having a conical end which engages a similarly shaped recess in the end of the link 135 to form a pivot for the link and an operative connection between the link and the lever 122. In case movement of the raceway should be obstructed, for example by clogging of tacks between the raceway and separator, power movement of the lever 122 may still take place without danger of breakage or straining of parts, the spring plunger 139 in that case merely passing partially or wholly out of the recess in the link 135. From Fig. 3 it will be seen that the plunger 139 is sufficiently eccentric to the fulcrum 24 of the lever 122 to give the required movement to the raceway and that when the parts are in the position there shown the fulcrum 24, the plunger 139, and the ball joint 137 are substantially in a straight line, and also 50 that the face of the lever along which the block 132 is adjustable is substantially perpendicular to this line. The block 132 can, therefore, be adjusted without materially varying the position of the raceway when the parts are in the position shown; such adjustment of the block, however, will vary the movement imparted to the raceway when the lever is moved and provides convenient and accurate means for alining with the separator the channel 17 of the raceway which is in operative relation to the separator when the lever is moved from the position of Fig. 3 to its other position. The tack channel 16 may be alined with the separator while the 55 parts are in the position of Fig. 3 by loos-

ening the set nut 138 and turning the ball ended portion of the link 135. The thin edge gage 13 is arranged for horizontal sliding movement into and out of operative position on a member 140 secured at 142 to the machine frame (Fig. 2), while the thick edge gage 14 is arranged for movement into and out of operative position in a path inclined to the horizontal, being adjustably secured by a cap screw 144 to a block 146 which is 75 gibbed to inclined ways on the member 140.

The block 146 has a vertical slot 148 in its side (Fig. 3) in which a block 150 is arranged for lateral sliding movement. A pin 152 secured to a downwardly and inwardly projecting portion 154 of the lever 122 passes freely through the block 150 so that as the lever 122 is swung the thick edge gage 14 is moved into and out of operative position in an inclined direction, the vertical component of that movement being taken care of by vertical sliding movement of the block 150 on the pin 152 while the lateral play of the block in the slot 148 enables the curvilinear movement of the lever to be 90 translated into rectilinear movement of the gage and block 140. When the thick gage 14 is advanced the thin gage 13 is retracted by means of a link 156 connected between the lower end of the pin 152 and one end of a lever 158 fulcrumed at 160 between its ends and having its opposite end connected to one end of a link 162 the other end of which is secured by a bolt and slot connection 164, 166 to the thin gage 13. By adjusting the bolt 164 in the slot 166 the operative position of the thin gage may be varied.

It will be seen from Fig. 1 that the shaft 27 and rod 46 are extended downwardly so that when it is desired to raise the head 105 of the machine on the column to accommodate a taller operator it is only necessary to release the various clamp screws holding the parts, raise the head, and then tighten the screws again.

On the shaft 6 is a gear 170 which meshes with a gear 172 (Fig. 9) by which the tack lifting vanes or buckets of the tack pot 174 are operated. The tack pot has two chambers separated by a partition 176 and on the outer side of each chamber is a member 178 fixed to a shaft 180 which extends through a sleeve 182 passing through the tack pot, said shaft having fixed thereto the gear 172. The inner faces of the members 178 are provided with tack lifting vanes 184 by which tacks are lifted and dropped upon tack hoppers 186 which are inwardly and forwardly inclined to conduct the tacks to the inner ends of the raceway channels 16, 17. In order to control the rate of passage of the tacks to the chambers the hoppers are so arranged that their inclination may be varied. For this purpose inclined faces 190 are formed on lateral projections of the par-

70

120
125

130

tion 176 of the tack pot. Each of the hoppers has an ear 192 which is secured by a cap screw 194 to one of the inclined faces 190. By loosening the screws the inclination of the hoppers relatively to the raceway may be varied to control the passage of tacks to the raceway. The surfaces 190 extend forwardly of the hoppers and are arranged to assist in directing the tacks toward the tack channels 16, 17 of the raceway 136. For convenience of manufacture the raceway 136 is made in two parts rigidly secured together by screws 196. The upper part of the raceway is bifurcated, each branch thereof passing freely through a hole in the tack pot wall, the raceway being therefore virtually pivoted in the tack pot wall so that the lower end of the raceway may be moved the distance required to effect the change in the size of tacks supplied to the separator. The lower end of the raceway must extend in close relation to a tack gate 200 and a separator blade 202 (Fig. 10) which are reciprocated across its end by means usual in such machines which engages a rack 204 connected with the gate and blade 202. The separator blade 202 is of the usual construction, shown, for instance, in United States Letters Patent No. 1,030,315, granted June 25, 1912, on application of Ronald F. McFeely. To enable adjustment of the raceway relatively to the separator to be accurately and conveniently effected means shown in Figs. 9 to 11 is provided. A bracket 206, which supports the raceway, is provided with a tongue 208 which engages a slot 210 formed in the lower portion of the raceway, this arrangement permitting lateral movement and a slight longitudinal movement of the raceway but preventing vertical movement. Substantially midway of the raceway it is provided on its lower side with a lateral slot which is engaged by a guide block 212 (Fig. 11) pivoted on a stud 214 extending upwardly from a block 216. The block 216 is provided on its inner side with a tongue 215 engaging a groove in the bracket 206, the groove being parallel to the inclined top of the raceway. The block 216 is clamped to the bracket by a cap screw 218 extending through a slot in the block and threaded into the bracket 206. At right angles to the screw 218 is a screw 220 threaded through the block 216 and engaging the screw 218. By loosening the screw 218 and turning the screw 220 it will be obvious that the block 216 and the guide block 212 may be moved in the direction of the length of the raceway and will carry the raceway with them while at the same time lateral movement of the raceway to effect the shifting of tacks will be permitted. By this arrangement the lower end of the raceway may be adjusted very accurately with relation to the sepa-

rator so as to permit free movement of the separator.

In Fig. 10 the separator is represented in cross-section in the position which it assumes when the tack has just been separated and is in the act of dropping through the tack passage 222 which is formed in the stationary separator block 224. This passage is open on the side toward the tacks at the time when the separator blade 202 selects the lowermost tack and causes it to pass into the passage 222 and is then closed by the gate 200, the tack then having a closed passage through which to drop from the separator through an opening 226 in the separator support and into the tack pocket of the wiper 15 which at that time is positioned beneath it.

The tack channels 16, 17 are formed by plates 230 attached to the body of the raceway 136 in spaced relation therefrom by bolts 232. In the present construction these plates are made sufficiently wide and the raceway sufficiently deep to accommodate tacks of greater length than have heretofore been called for in machines of this type, 4-ounce tacks or larger being provided for. With the top of the raceway down which the edge of the tacks slide inclined at an angle of 30 degrees, which is the usual angle in machines of this type and which has been found sufficient to ensure reliable travel of the tacks by gravity, it is found that the stems of the tacks, instead of hanging in a vertical position, are inclined inwardly away from the separator at an angle of, say, 10 or 12 degrees to the vertical. In the prior construction the tack gate 200 and the tack passage 222 were vertical and difficulty was found in securing reliable tack separation. This failure of the separator to separate tacks was found to be due to the difference between the natural hanging angle of the tacks in the raceway and the plane of the tack gate and the direction of the tack passage 222. Accordingly in the present construction the plane of action of the tack gate 200 and the direction of the tack passage 222 are made to approximate the natural hanging angle of the tack with the result that a tack is secured upon each reciprocation of the separator blade 202.

The gripper 10 is connected to the forward end of an updraw lever 240 pivoted between its ends at 242 to lugs 243, 245 on the frame and connected through a spring 247 to a slide 244 which is operated by a suitable cam on the shaft 6. The closing movement of the gripper is effected by a rockshaft 246 which has two arms, one arm 248 operating through a link 250 to thrust downwardly upon the movable jaw of the gripper and the other arm 252 carrying a roll 253 which is acted upon by a gripper closing cam 254. The rockshaft 246 is

journaled near its forward end in a lug 255 on the lever 240 and at its rear end (Figs. 7 and 8) is journaled in an ear 256 on the pivot pin 242 of the lever 240. By this construction the rockshaft 246 partakes of the movement of the lever 240 and in consequence the roll carrying end of the arm 252 has a movement transverse to the face of the cam 254 which has a fixed axis. When the cam roll is of usual construction the resistance of the roll to transverse movement causes a retardation of the updraw movement of the lever 240 as well as excessive wear on the roll and cam. Also the longitudinal thrust on the pin 242 by the action of the cam 254 causes undue friction of the lever on the lugs 243, 245 which further interferes with the full updraw effect of the spring 247 upon the gripper. To overcome these objectionable features of the prior construction the construction shown in Figs. 7 and 8 is provided. The roll 253 is movable longitudinally of its pivot pin 258 and ball bearings are provided for the roll which not only allow free turning of the roll on the pin 258 but also permit the pin to move freely longitudinally in the roll as the arm 252 is moved to and fro in the direction of the arrow in Fig. 7 during the updraw movement. This construction obviates the drag due to the resistance of the roll, as usually constructed, to transverse movement relatively to the face of the cam 254. To overcome the binding of the updraw lever 35 on its bearing, due to the longitudinal stress on the pin 242, a ball thrust bearing is provided on the end of the pin opposite to the arm 252. The bearing comprises a washer 260 loose on the pin 242 and in contact with the lug 245 of the frame, a washer 262 splined on the pin, and a ball cage 264 between the washers 260, 262. The end of the pin is threaded to receive a nut 266 and a set nut 267. The pin 242 is held in the lever 240 by a set screw 268 so that the pin has to move with the lever 240 and binding of the ear 256 on the rockshaft 246 is prevented. Since the pin 242 is fixed in the lever 240 the thrust bearing may be adjusted by the nuts 266, 267 so as to permit free movement of the lever with relation to the lug 245 and to prevent frictional contact of the lever 240 with the lug 243, the longitudinal thrust of the pin 242, due to the action of the cam 254 on the roll 253 being taken entirely by the ball thrust bearing 264.

Various novel features of the construction of the illustrated machine including the mechanism for automatically shifting the edge gages, herein shown and described but not claimed, is being disclosed and claimed in my copending application Serial No. 641,685, filed May 26, 1923, which is in part a continuation of this application.

Having thus described my invention, what

I claim as new and desire to secure by Letters Patent of the United States is:

1. In a machine of the class described, the combination of an inclined raceway having a plurality of tack channels down which tacks travel supported by their heads with their stems inclined out of the vertical in a direction away from the end of the raceway, and a separator for the tacks arranged to separate tacks from either channel and having a delivery passage inclined to the vertical at an angle approximating the natural hanging angle of the tacks in the raceway. 70

2. In a machine of the class described, the combination of an inclined raceway having a plurality of tack channels down which tacks descend by gravity and supported with their stems disposed at an angle to the vertical constituting the natural hanging 85 angle of the tacks, a single tack separator constructed and arranged to reciprocate across the end of either channel in the raceway and to separate tacks one at a time from either column of tacks in the raceway, and a block supporting the separator and having a passage through which the tacks fall after separation, said passage being inclined to the vertical at an angle approximating the natural hanging angle of the tacks. 90

3. In a machine of the class described, the combination of a raceway having a plurality of tack channels along which tacks are impelled by gravity while supported by their heads in such a manner that their stems are disposed out of the vertical, a separator block at the end of the raceway having a tack passage open on the side toward the raceway, said passage being inclined to the vertical at substantially the hanging angle 100 of the tacks, a single separator blade arranged for reciprocation and acting to separate a tack from a column of tacks in either channel of the raceway and to transfer the tack through the slot in the passage, 105 and a gate to close the slot and form a passage with continuous walls after the tack is released by the blade. 110

4. In a machine of the class described, the combination of a raceway having a plurality of tack channels along which tacks are impelled by gravity while supported on their heads in such a manner that their stems are disposed out of the vertical, a separator block at the end of the raceway having a single tack passage open on the side toward the raceway, the raceway being shiftable to align either channel with the opening, a separator blade arranged for reciprocation and acting to separate a tack from a column of tacks in the raceway and to transfer the tack through the opening into the passage, and a gate to close the opening and form a passage with continuous walls for the tack when released by the 130

blade, said gate being arranged for reciprocation in a plane approximating the natural hanging angle of the tack in the raceway.

5. In a machine of the class described, the combination of an inclined raceway having a plurality of tack channels down which tacks travel supported by their heads with their stems inclined out of the vertical in a direction away from the end of the raceway, 10 a reciprocating separator for the tacks including a tack gate inclined to the vertical at an angle approximating the natural hanging angle of the tacks in the raceway, and means for shifting the raceway to align 15 either channel with the separator.

6. In a machine of the class described, the combination of an inclined raceway having a plurality of tack channels down which tacks descend by gravity and supported with 20 their stems disposed at an angle to the vertical constituting the natural hanging angle of the tacks, a single tack separator including a tack gate constructed and arranged to reciprocate across the end of the raceway and to separate at will tacks one 25 at a time from either column of tacks in the raceway, and a block supporting the separator and having a passage through which the tacks fall after separation, said 30 passage being closed at its side by the gate and said gate being inclined to the vertical at an angle approximating the natural hanging angle of the tacks.

7. In a machine of the class described, 35 the combination of a swinging raceway having a plurality of tack channels along which tacks are impelled by gravity while supported on their heads in such a manner that their stems are disposed out of the vertical, 40 a separator block at the end of the raceway having a tack passage open on the side toward the raceway, means for swinging the raceway to align either tack channel with the tack passage of the separator block, a 45 separator blade arranged for reciprocation and acting to separate a tack from a column of tacks in the raceway and to transfer the tack through the opening into the passage, and a gate to close the opening and form a 50 passage for the tack when released by the blade, said gate being arranged for reciprocation in a plane inclined to the vertical at approximately the natural hanging angle of the tack in the raceway.

8. In a machine of the class described, 55 a raceway for tacks, a tack separator at one end of the raceway, a tack pot at the other end of the raceway into which the raceway freely extends and in the wall of which it is loosely supported, and means outside of the tack pot for adjusting the raceway longitudinally in the tack pot relatively to the separator.

9. In a machine of the class described, a 60 tack pot, a separator, a raceway having tack

channels leading from the tack pot to the separator, said raceway passing freely through the tack pot wall to permit transverse movement of the raceway with respect to the separator, and means for supporting 70 the raceway between its ends comprising a block mounted for adjustment lengthwise of the raceway and a guide pivoted to the block and engaging a transverse slot in the raceway. 75

10. In a machine of the class described, a tack pot, a separator, a raceway having tack channels extending from the interior of the tack pot to the separator, the raceway being supported in the tack pot wall and at its 80 lower end for lengthwise movement, a support for the raceway located between the ends of the raceway, outside of the tack pot, arranged to permit lateral movement of the raceway and to prevent longitudinal movement thereof, and readily accessible means for effecting a fine adjustment of the support to vary the longitudinal position of the raceway relatively to the separator. 85

11. In a machine of the class described, 90 the combination of a raceway support, a raceway provided with a plurality of tack channels and arranged for lengthwise and transverse movement on the support, a separator with respect to which the raceway is 95 moved lengthwise for adjustment of the end of the raceway in proper operative relation to the separator and is shifted transversely to bring either raceway into operative relation to the separator, a block mounted on 100 the support for movement lengthwise of the raceway, a guide pivoted to said block and engaging a transverse slot in the raceway, and a fine adjustment for moving the block and guide to effect lengthwise adjustment of the raceway. 105

12. In a machine of the class described, 110 the combination of a tack pot, a separator, a raceway having a plurality of tack channels which are continuous from the interior of the tack pot to the separator, the raceway being movable as on a pivot at its point of passage through the tack pot wall, an edge gage arranged to slide into and out of operative position, and power operated means under control of the operator for shifting the lower end of the raceway to align the different channels with the separator and for shifting the edge gage into 115 and out of operative position. 120

13. In a machine of the class described, 125 the combination of a tack pot, a separator, a raceway having a plurality of tack channels continuous from the interior of the tack pot to the separator and having a lateral slot in its under side, the raceway being movable as on a pivot at its point of passage through the tack wall, means for shifting the lower end of the raceway for aligning different channels with the separator, a 130

block for engaging the lateral slot in the raceway, and means for adjusting the block longitudinally of the raceway, said slot permitting lateral shifting movement of the raceway.

14. In a machine of the class described, a raceway having a plurality of tack channels, a push and pull rod connected to the raceway, a separator, mechanism for operating the rod to present either channel in operative relation to the separator, and a yielding connection between the rod and said mechanism, said connection being adapted to yield upon movement of the shifting mechanism in either direction in case movement of the raceway is obstructed.
15. In a machine of the class described, a raceway having a plurality of tack channels, a separator, power means for shifting the raceway to present either channel in oper-

ative relation to the separator, and slip connections between the raceway and said power shifting means normally operative to shift the raceway and constructed and arranged to permit relative movement between the raceway and the shifting means under abnormal strain to prevent breakage of parts. 25

16. In a machine of the class described, a raceway having a plurality of tack channels, a separator, power means for shifting the raceway to present either channel in operative relation to the separator, and connections between the raceway and said power shifting means comprising a link having a 30 conical recess and a spring-pressed plunger on the power shifting means.

In testimony whereof I have signed my name to this specification.

THOMAS H. SEELY.
